CLAIM

The ornamental design for a patch and swivel for a drift control parachute for a boat, as shown and described.

DESCRIPTION

FIG. 1 is a side elevational view showing a patch and swivel for a drift control parachute which forms our new design, the boat, parachute and tether lines which are shown in phantom being for illustrative purposes only and forming no part of our design;

FIG. 2 is an enlarged right side elevational view of the patch and swivel affixed to the drift control parachute of FIG. 1, this side and the opposite left side elevational views being of identical design;

FIG. 3 is a top plan view thereof;

FIG. 4 is a front elevational view thereof, this view and the opposite rear elevational view being of identical design; and,

FIG. 5 is a bottom plan view thereof.
